G. P. SEILER.

SIGNAL.

APPLICATION FILED FEB. 12, 1917.

1,248,177.

Patented Nov. 27, 1917.

UNITED STATES PATENT OFFICE.

GEORGE P. SEILER, OF DETROIT, MICHIGAN, ASSIGNOR OF ONE-HALF TO WILLIAM R. BLENMAN, OF DETROIT, MICHIGAN.

SIGNAL.

1,248,177.

Specification of Letters Patent. Patented Nov. 27, 1917.

Application filed February 12, 1917. Serial No. 148,084.

To all whom it may concern:

Be it known that I, GEORGE P. SEILER, a citizen of the United States of America, residing at Detroit, in the county of Wayne 5 and State of Michigan, have invented certain new and useful Improvements in Signals, of which the following is a specification, reference being had therein to the accompanying drawings.

10 This invention relates to signals and has special reference to an exhibitor that may be advantageously used in connection with automobiles or similar vehicles for indicating to another vehicle when the exhibitor carrying vehicle is about to stop or turn into another lane of travel.

The primary object of my invention is to provide a simple durable and inexpensive signal exhibitor that will provide a constantly illuminated tail light at night and wherein sign members are employed for displaying suitable signs, one of which may be easily shifted into a display position and illuminated at night.

25 A further object of my invention is to provide a compact signal exhibitor wherein a spring actuated roller is employed for maintaining one sign normally displayed and another sign in position to be swung to the display opening of the exhibitor when the signal is actuated.

The mechanical construction by which I attain the above and other objects will be hereinafter specifically described and then 35 claimed, and reference will now be had to the drawing, wherein—

Figure 1 is a vertical sectional view of the signal exhibitor;

Fig. 2 is a longitudinal sectional view of 40 the same, and

Fig. 3 is a perspective view of sign members as supported by a roller.

The signal exhibitor comprises a casing having a bottom plate 1, side walls 2, a rear wall 3, an inverted V-shaped roof or top plate 4, and a hinged front wall 5. The hinged front wall 5 is connected to the front edge of the bottom plate 1, as at 6 so that it may be swung downwardly to permit of 50 easy access being had to the interior of the exhibitor casing, and the upper edge of the front wall is adapted to be held by a suitable snap fastener 7 or similar holding means carried by the apex of the roof or top plate

4. The upper part of the hinged front wall 55 has a bulls eye or lens 8 and the lower part thereof is provided with an oblong sight opening 9 closed by a transparent plate 10.

The inner side of the rear wall 3 has a 60 suitable incandescent lamp 11 and the bulb of this lamp may be red in color or the bulls eye or lens 8 of a similar color, so that a danger signal will be displayed when the lamp is illuminated from a suitable source 65 of electrical energy, as batteries (not shown). Since the interior of the exhibitor casing may be illuminated, the bottom plate 1 thereof is provided with an oblong opening 12 so that rays of light may be cast upon the 70 front side of a license plate, card or tag, suitably connected to the rear wall 3 of the exhibitor casing.

The inner sides of the walls 2 are provided with suitable brackets 14 for the pinnacles 15 of a spring actuated roller 16, said roller being somewhat similar to ordinary curtain shade rollers. Suitably connected to the periphery of the roller 16 are sign members 17 and 18 disposed at right angles to 80 each other, with the sign member 18 of greater width than the sign member 17 and the latter provided with end stops 19 to engage the bottom plate 1, as best shown in Fig. 1, and thereby hold the sign member 18 85 in parallelism with the front wall 5 of the casing, thus permitting of the sign carried by the sign member being displayed at the sight opening 9 of the casing. As shown in Fig. 3, it is preferable to provide the sign member 18 with the words "Safety First" 90 and the sign member 17 with the word "Stop." The "Stop" sign member will normally confront the bottom plate 1 of the exhibitor casing and to swing this sign member into an active position so that the sign may be observed at the sight opening 9, a cable 20 extends into the exhibitor casing and is attached to the roller 16, as at 21.

An opening 22 in the rear wall 3 of the exhibitor casing provides clearance for the cable 20 and this cable may extend to a clutch pedal, brake lever, or steering wheel in order that it may be conveniently pulled to partially rotate roller 16 against the action 100 of the spring thereof, and display the "stop" sign.

The inner side of the hinged front wall 5

of the exhibitor casing has a longitudinally disposed ledge or partition 23 extending into proximity of the longitudinal edge of sign member 18, but this partition does not interfere with a partial rotation of the roller 16. It coöperates with the sign member 18 in confining light rays within the exhibitor casing, but when the sign member 17 is swung to an active position, then there is a space between said sign member and the partition that permits of light rays from the lamp 11 illuminating the "stop" sign of the signal.

I attach considerable importance to the simplicity of the signal exhibitor, as the casing thereof may be made of light and durable metal, non-corrodible, and finished to harmonize with the metallic fittings of an automobile or similar vehicle, and while in the drawing there is illustrated a preferred embodiment of my invention, it is to be understood that the structural elements are susceptible to such changes in size, shape and manner of assemblage as fall within the scope of the appended claim.

Copies of this patent may be obtained for five cents each, by addressing the "Commissioner of Patents, Washington, D. C."

What I claim is:—

An exhibitor for signals comprising a casing having a hinged front wall provided with sight openings, a longitudinal ledge carried by the inner side of said hinged front wall between the sight openings thereof, a roller journaled in said casing, sign members carried by said roller with one of said members coöperating with said ledge in providing an inclosure at one of said sight openings, illuminating means within said casing, means in said roller adapted for rotating said roller in one direction, stops carried by one of said sign members at each end thereof engaging the bottom of said casing and holding said roller normally stationary, and means attached to said roller and extending out of said casing adapted for partially rotating said roller.

In testimony whereof I affix my signature in the presence of two witnesses.

GEORGE P. SEILER.
